D. 96,867 9/1935 Stipek D6/186

Primary Examiner—Lester L. Lee

[57] CLAIM

The ornamental design for a cabinet, as shown and described.

DESCRIPTION

FIG. 1 is a perspective view of the cabinet taken from the rear showing my new design. The bottom is plain and unornamental.

FIG. 2 is a front elevational view thereof.

FIG. 3 is a side elevational view thereof.

The side shown is identical to that which is not.
